UNITED STATES PATENT OFFICE.

FRED E. WHITE, OF GARDNER, MASSACHUSETTS, ASSIGNOR TO FLORENCE STOVE COMPANY, OF GARDNER, MASSACHUSETTS, A CORPORATION OF MASSACHUSETTS.

AIR DISTRIBUTOR.

Application filed September 3, 1924. Serial No. 735,669.

To all whom it may concern:

Be it known that I, FRED E. WHITE, a citizen of the United States, and resident of Gardner, in the county of Worcester and 5 State of Massachusetts, have invented certain new and useful Improvements in Air Distributors, of which the following is a specification.

My present invention relates to an air 10 screen or distributor of the type usually required in oil stoves of the type using a cylindrical wick, the air for combustion feeding through the center of the distributor and passing out through perforations 15 therein.

The principal object of the invention is the provision of means which will prevent flickering of the flame with its accompanying incomplete combustion, which thereupon 20 insures a more efficient operation of the stove and which otherwise insures an even burning steady flame.

To this end my invention comprises a flame spreader and air distributor having a 25 stove attaching part to which is secured a perforated annular part carrying a flame spreading cap, the interior of the device having a substantially cylindrical perforated skirt extending down well toward the 30 bottom of the perforated portion.

I have illustrated in the accompanying drawings one form of device as being satisfactory, although obviously many other forms will occur to those skilled in the art.

In these drawings:—

Figure 1 is a side elevation of the device of my invention showing the wick and wick tube in section.

Fig. 2 is a sectional side view of the air distributor of Fig. 1.

Fig. 3 is a bottom plan view of the device of Fig. 2.

Referring now to the embodiment illustrated I have shown an air distributor having a toothed portion 1 adapted to be secured to the annular wick holder 2 in the usual manner, and provided with a perforated upper portion 3 having a shoulder 4 adapted to rest upon the upper portion 5 of the wick 5 in the usual manner. A flame spreading cap 6 surmounts the structure as usual. The upper portion of the perforated part 3 is turned inwardly and is provided with an enlarged circular opening 7 concentric with the vertical axis of the device. To

the rim of the opening 7 is attached a cylindrical skirt 8 having perforations 9 therein. The bottom of the skirt 8 projects well down toward the bottom of the juncture of the perforated portion 3 with the toothed portion 1. A right-angular ring 10 is secured between the parts 1 and 3 and projects upwardly for a short distance between the skirt 8 and the perforated portion 3. The ring 10 is provided with perforations on its 60 horizontal face, as clearly shown.

In the operation of the device it will be apparent that in order for the air to reach the flame it must pass upwardly either through the perforations of the skirt 8, or 70 between the skirt and the ring 10, and from those out through the perforations in the portion 3.

If sufficient space is left between the skirt and the remainder of the device for air to 75 feed the flame, then the skirt need not necessarily be perforated, as its chief function is to check transverse currents from affecting the flame. However, the perforations add to the effectiveness of operation. 80

Having thus described my invention, what I claim is:—

1. An air distributor for wick stoves, having an annular perforated wall and a 85 perforated skirt depending from said wall with a right-angular ring adjacent the bottom part of the annular perforated wall and between the bottom part of the skirt and the perforated wall.

2. An air distributor for wick stoves, 90 having an annular perforated wall and a perforated skirt depending from said wall with a right-angular ring adjacent the bottom part of the annular perforated wall and between the bottom part of the skirt and the 95 perforated wall, and an annular channel between the bottom of the skirt and the right-angular ring.

3. An air distributor for wick stoves having an annular perforated wall and a skirt 100 depending vertically from said wall.

4. An air distributor for wick stoves, having an annular perforated wall, and means within the confines of said wall to check air currents passing from one side of the distributor to the other comprising a perforated tube of a diameter greater than one-half the diameter of the chamber within which it is located. 105

5. In combination, a wick tube, a wick 110

therein, said wick having an exposed portion, an air distributor supported upon said wick, and having a perforated portion above the wick top supplying air to the flame produced by the burning of the oil in the exposed part of said wick, and perforated means to check air currents passing from one side of said perforated portion to the other.

6. In combination, a wick tube, a wick therein, said wick having an exposed portion, an air distributor having a perforated portion above the top of the wick and supplying air for a flame produced by burning of the oil in the exposed part of the wick, and a depending perforated skirt within the distributor to check air currents passing from one side of said perforated portion to the other.

7. In combination, a wick tube, a wick therein, said wick having an exposed portion, an air distributor extending within the wick tube and having a perforated portion above the top of said wick, said air distributor supplying air to an annular flame produced by oil burning from the exposed portion of the wick, and a perforated skirt within the distributor and between the flame walls, to check air currents passing from one side of the distributor to the other.

8. In combination, a wick tube, a wick therein, said wick having an exposed portion, an air distributor supplying air to an annular flame produced by oil burning from

the exposed part of the wick, from the center of said distributor outwardly toward the 35 inside of the flame annulus, and a perforated skirt within the distributor and between the flame walls checking air currents passing from one side of the distributor to the other.

9. An air distributor for wick stoves producing an annular flame, having a perforated portion occupying a position axially of and between the normal location of the flame walls, and a perforated wall between the 45 perforated sides of the air distributor checking air currents passing from one side of the distributor to the other.

10. An air distributor for wick stoves producing an annular flame, having a perforated portion supplying air to the inside of the flame annulus, the perforated portion occupying a position between the normal position of the flame walls, and a cylindrical skirt within the distributor and also between the flame walls.

11. An air distributor for wick stoves producing an annular flame, provided with a perforated portion supplying air to the inside of the flame annulus, and a perforated 60 skirt within the distributor obstructing free passage of air currents from one side of the distributor to the other.

In testimony whereof I affix my signature.

FRED E. WHITE.
